UNITED STATES PATENT OFFICE.

JOHN MCINTYRE, OF PORTOBELLO, MIDLOTHIAN, SCOTLAND, ASSIGNOR OF ONE-HALF
TO JAMES MILNE AND SON LIMITED, OF EDINBURGH, SCOTLAND.

GRINDING, REFINING, AND MIXING MACHINE.

Application filed February 18, 1924. Serial No. 693,686.

To all whom it may concern:

Be it known that I, JOHN MCINTYRE, of 28 Brighton Place, Portobello, Midlothian, Scotland, engineer, have invented certain new and useful Improvements in and Connected with Grinding, Refining, and Mixing Machines, of which the following is a specification.

My invention relates to improvements in connection with machines for grinding, refining and mixing cocoa-beans, chocolate, chemicals and such like substances, and has for its object to provide a more efficient gear so that any desired pressure can be exerted 10 on the grinding surface or released entirely while the machine is in motion or stationary.

A further improvement of my invention is to improve the construction of the flexible blades and the inner wall of the cylinder 20 which forms the grinding surface in such a manner that the material being ground or refined in the machine is reduced in a shorter period than previously could be accomplished. Also, by this construction, we provide 25 a simple means whereby the grinding surface can be easily examined and renewed if necessary.

In carrying out my invention, I provide a jacketed cylinder having covers suitably 30 fixed to each end. The jacket is arranged so that water or steam can be circulated through it for the purpose of keeping the cylinder at any desired temperature. The driving shaft, which in the present arrangement is rotated by means of a worm wheel 35 and shaft, has fixed to its inner end a wheel which carries pins. On these pins rockers or quadrants are mounted which are made to swing through a pre-determined arc by 40 means of pins fixed to each rocker and engaging with notches cut in a ring which is mounted and free to turn on the wheel. Suitable gearing is provided for the purpose of operating the rockers to which the flexible 45 blades are attached in such a manner that the grinding surfaces of the blades can be made to press on the grinding surface of the cylinder wall or be released from contact with the cylinder wall when desired, while 50 the machine is in motion or stationary.

In my present arrangement, I fix one or more round hard metal bars on to each flexible blade. Similar bars may be fixed to the inner wall of the cylinder, so as to provide 55 a grinding surface which will be lasting and

at the same time permit them to be easily taken out and examined and renewed if found necessary. It is to be understood that bars of other than round section may be used.

An annular chamber is provided at the inner end of the driving shaft bearing by fitting a lantern ring in such a manner that any oil passing this point on the driving shaft is drained by means of a pipe back to 60 the oil sump or bath. This oil sump or bath maintains the lubrication of the whole machine.

In order that my invention may be properly understood and readily carried into effect, I have hereunto appended two sheets of drawings, of which

Figure 1 is a sectional front elevation illustrating my invention and a detached view of the key-way and sleeve.

Figure 2 is an outside front elevation of cover containing gears.

Figure 3 is a sectional side elevation through gears.

Figure 4 is a sectional side elevation through cylinder showing arrangement of rockers.

Figure 5 is a view showing the rockers in position before tightening.

Figure 6 is a view showing rockers in 85 position when tightening has been effected.

Figure 7 shows different forms of grooves for inside of cylinder wall.

Referring to the drawings, the jacketed cylinder A has covers B¹ and B² suitably 90 fixed to its ends. Water or steam may be circulated through the annular space C which forms the jacket, for the purpose of keeping the cylinder at any desired temperature. The driving shaft X, which, in the present arrangement, is rotated by means of the worm wheel D and the worm shaft E, passes through end cover B¹ and has fixed to its inner end the wheel F. This wheel carries the fixed pins G on which the rockers or quadrants H are mounted. These rockers are made to swing through a pre-determined arc by means of the pins I which are fixed to each rocker and engage with notches cut in the ring J. This ring is 105 mounted and free to turn on the wheel F.

The flexible blades K are mounted on the rockers H and in the present arrangement carry four round metal bars L, which grind or refine the material being dealt with in 110

the machine when they are tightened against the cylinder wall. The driving shaft X is bored to take the spindle M. This spindle rotates with the driving shaft and is free to move in a longitudinal direction through it. The outer end of the spindle M is reduced and passes through the external threaded sleeve N in which it is free to rotate and is prevented from having any end movement with relation to the sleeve by having the ball-race R¹ fitted between the sleeve and the washer P at one end and the ball-race R² and the shoulder Q at the other. The nut U is threaded to take the sleeve N and is suitably fixed to the worm wheel V by which it is rotated, and also prevented from having any end movement through the worm wheel V being a working fit between the faces D¹ and D². Said wheel V is keyed to the nut U as at T. The worm shaft A¹ engages with the worm wheel V and is operated by means of the hand-wheel A². The flange E¹ and the worm-wheel D are bolted to the driving shaft X in such a manner that a recess is made to take the two ball-races F¹ and F² with the collar G¹ which is formed on the nut U between; thus preventing any lateral movement of the driving shaft X. Two of the rockers H are extended and the swivel joints H¹ and H² fitted to their ends to take one end of the rods J¹ and J², the other ends of which are connected with the inner end of the spindle M so as to form a joint by the pin K¹. The dome O¹ has a slot cut in it to take the indicator P¹ which is attached to the sleeve N for the purpose of indicating the amount of pressure on the grinding surfaces. The material to be ground is supplied to the machine through the hoppers Q¹ and Q² and a suitable valve is fixed at the bottom of the end cover B², but not shown, for the purpose of running off the refined material. In tightening the grinding surface of the flexible blades against the cylinder wall or releasing them the hand-wheel A² is turned in one direction then through the worm shaft A¹ and the worm wheel V the threaded nut U is rotated, thus moving the sleeve N towards the dome O¹ and drawing the spindle M in that direction, tightening the grinding surface of the flexible blades against the cylinder wall through the rods J¹ and J² and the two rockers H to which the rods are connected. Those two rockers operate all the others through the ring J and the pins I. If the hand-wheel A² is turned in the opposite direction the spindle M is moved away from the dome O¹ thus releasing the flexible blades from the wall of the cylinder. In the present arrangement, I provide four round hard metal bars L suitably fixed to the blades K. The cylinder wall may be grooved to take the form as shown at S¹ or may be grooved to receive round metal bars as shown at

S². In this instance the metal forming the cylinder wall is caulked at V¹ to keep the bars in position. Bars other than round section may be used such as shown in Figure 7. To remove the rockers H so that the grinding surface may be examined or renewed, the end cover B² is removed and the rockers disconnected from the fixed pins G. The working parts of the machine which required lubrication are supplied from the oil sump or bath W. The splash of the worm-wheel D during rotation provides a constant supply to the various oil holes such as shown at 1, 2, 3, 4. Any oil passing along the driving shaft X is drained back to the oil sump or bath W through the lantern ring X¹ being fitted between the end of the bearing Y¹ and the packing Y², the pipe U¹ connecting up the annular space formed by the lantern ring and the oil sump or bath W.

Claims.

1. In a grinding and mixing machine a cylinder, a tubular shaft mounted in a bearing in the cylinder and having a wheel arranged in the cylinder, a spindle longitudinally movable in the bore of the tubular shaft, a free ring on said wheel and in said cylinder, rockers pivotally mounted on said wheel and provided with pins which are slideable in radial slots with which the free ring is provided, and pivotally connect the rockers to said ring, grinding elements on said rockers arranged to engage the inner periphery of the cylinder, connections between the rockers and the spindle, means to rotate the tubular shaft with its wheel and rockers, and means to longitudinally adjust the spindle to thereby adjust the grinding elements with respect to the inner periphery of the cylinder.

2. In a grinding and mixing machine a cylinder, a tubular shaft mounted in a bearing in the cylinder and having a wheel arranged in the cylinder, a spindle longitudinally movable in the bore of the tubular shaft, rockers pivotally mounted on said wheel, grinding elements on said rockers arranged to engage the inner periphery of the cylinder, spring connections between said rockers and said grinding elements, connections between the rockers and the spindle, means to rotate the tubular shaft with its wheel and rockers, and means to longitudinally adjust the spindle to thereby adjust the grinding elements with respect to the inner periphery of the cylinder, and also vary the tension of said spring connections.

3. In a grinding and mixing machine a cylinder, a tubular shaft mounted in a bearing in the cylinder and having a wheel arranged in the cylinder, a spindle longitudinally movable in the bore of the tubular shaft, rockers pivotally mounted on said wheel, spring elements on said rockers ar-

ranged to press toward the inner periphery of the cylinder, grinding elements on said spring elements engaged by the tension of the latter with the inner periphery of the cylinder, connections between the rockers and the spindle, means to rotate the tubular shaft with its wheel and rockers, and means to longitudinally adjust the spindle to thereby adjust the grinding elements with respect to the inner periphery of the cylinder.

4. In a grinding and mixing machine a cylinder, a tubular shaft mounted in a bearing in the cylinder and having a wheel arranged in the cylinder, a spindle longitudinally movable in the bore of the tubular shaft, rockers pivotally mounted on said wheel, grinding elements on said rockers arranged to engage the inner periphery of the cylinder, connections between the rockers and the spindle, means to rotate the tubular shaft with its wheel and rockers, and means to longitudinally adjust the spindle to thereby adjust the grinding elements with respect to the inner periphery of the cylinder, said adjusting means for said spindle comprising an exteriorly threaded sleeve mounted on said spindle and connected thereto for longitudinal movement therewith, a nut threadedly engaged with said sleeve, and means to turn said nut.

5. In a grinding and mixing machine a cylinder, a tubular shaft mounted in a bearing in the cylinder and having a wheel arranged in the cylinder, a spindle longitudinally movable in the bore of the tubular shaft, rockers pivotally mounted on said wheel, grinding elements on said rockers arranged to engage the inner periphery of the cylinder, connections between the rockers and the spindle, means to rotate the tubular shaft with its wheel and rockers, and means to longitudinally adjust the spindle to thereby adjust the grinding elements with respect to the inner periphery of the cylinder, said adjusting means for said spindle comprising an exteriorly threaded sleeve mounted on said spindle and connected thereto for longitudinal movement therewith, a nut threadedly engaged with said sleeve, and means to turn said nut, said means comprising a worm wheel secured to said nut and a worm engaging said worm wheel.

6. In a grinding and mixing machine a cylinder, a tubular shaft mounted in a bearing in the cylinder and having a wheel arranged in the cylinder, a spindle longitudi-

nally movable in the bore of the tubular shaft, rockers pivotally mounted on said wheel, spring elements on said rockers arranged to press toward the inner periphery of the cylinder, grinding elements on said spring elements engaged by the tension of the latter with the inner periphery of the cylinder, connections between the rockers and the spindle, means to rotate the tubular shaft with its wheel and rockers, and means to longitudinally adjust the spindle to thereby adjust the grinding elements with respect to the inner periphery of the cylinder, and also vary the tension of said spring connections and means to indicate the position of said spindle.

7. In a grinding and mixing machine a cylinder, a tubular shaft mounted in a bearing in the cylinder and having a wheel arranged in the cylinder, a spindle longitudinally movable in the bore of the tubular shaft, rockers pivotally mounted on said wheel, grinding elements on said rockers arranged to engage the inner periphery of the cylinder, connections between the rockers and the spindle, means to rotate the tubular shaft with its wheel and rockers, and means to longitudinally adjust the spindle to thereby adjust the grinding elements with respect to the inner periphery of the cylinder, said connections between the spindle and rockers comprising rods pivotally connected to said spindle, and swivel joints between said rod and said rockers, said swivel joints adapting said rods for universal angular movement with respect to said rockers.

8. In a grinding and mixing machine a cylinder, a tubular shaft mounted in a bearing in the cylinder and having a wheel arranged in the cylinder, a spindle longitudinally movable in the bore of the tubular shaft, rockers pivotally mounted on said wheel, grinding elements on said rockers arranged to engage the inner periphery of the cylinder, connections between the rockers and the spindle, means to rotate the tubular shaft with its wheel and rockers, and means to longitudinally adjust the spindle to thereby adjust the grinding elements with respect to the inner periphery of the cylinder, spring plates on the rockers arranged tangentially with reference to the inner periphery of the cylinder, and grinding elements on said spring plates.

In testimony whereof I affix my signature.

JOHN McINTYRE.
